6 Sheets-Sheet 3

A technical line drawing of a conveyor system, labeled 'Fig. 5' at the top. The drawing shows a rectangular frame 8 with a door 5. A conveyor belt 21 is supported by a series of rollers and troughs. A vertical support structure 3 is on the right, featuring a vertical conveyor 53 and a horizontal conveyor 26. Various components are labeled with numbers: 6, 7, 20, 17, 18, 19a, 21, 25, 54, 55, 52, 50, 51, 3, and 4. The drawing illustrates the complex mechanical assembly of the conveyor system.

HYDRAULIC SIZER

Charles E. Wood, Milwaukee, Wis.

Application February 15, 1936, Serial No. 64,029

14 Claims. (Cl. 209—273)

My invention relates to a sizing, screening or classifying means and has for one purpose the provision of means for separating a mixed mass of particles by size, with the isolation of the larger from the smaller particles. Another object is the provision of a separating medium and means for preventing its apertures from blinding. Another object is the provision of means for separating articles by size, in connection with the employment of liquid or gaseous means for preventing blinding of the bed. Another object is the provision of improved means for feeding material for separation or sizing. Another object is the provision of improved means for taking off the oversize. Other objects will appear from time to time in the course of the specification and claims.

I illustrate my invention more or less diagrammatically in the accompanying drawings, wherein—

- 20 Figure 1 is a plan view;
- Figure 2 is a side elevation;
- Figure 3 is a vertical axial section, taken on line 3—3 of Figure 2;
- Figure 4 is a section on the line 4—4 of Figure 3;
- Figure 5 is a section on the line 5—5 of Figure 4;
- Figure 6 is an enlarged section on the line 6—6 of Figure 4;
- 30 Figure 7 is a plan view on an enlarged scale, with parts broken away, illustrating the top of the separating or sizing bed;
- Figure 8 is a section on the line 8—8 of Figure 7;
- 35 Figure 9 is a perspective of a variant form of the device;
- Figure 10 is a vertical longitudinal section on the line 10—10 of Figure 9;
- Figure 11 is a sectional view similar to Figure 10 of a further variant form; and
- 40 Figure 12 is a fragmentary section illustrating a variant form of water inlets.
- Like parts are indicated by like symbols throughout the specification and drawings.
- 45 Referring to the drawings, 1 indicates any suitable foundation upon which the device is mounted. 2 indicates any suitable base structure, for example of channel iron, which may be bolted or otherwise secured to the foundation. 3 indicates upstanding structural members for supporting the device which may be connected, for example, by cross pieces or angles 4. Preferably I employ four of the supports 3 arranged on a base 2 which is shown as rectangular. This structure will be clear from Figure 1 and the members

4 may be conveniently formed of angle irons. The members above described may, for example, be welded together.

Mounted upon the upper end of the members 3 is a channel or ring structure generally indicated as 5 which is shown as having a bottom 6, an inner cylindrical wall 7, and an outer cylindrical wall 8. At one or more points, and I have shown only one, is an aperture 9 having an outlet spout 10 communicating with any suitable member such as a run off trough 11. Mounted on the inner wall 7 is a channel 12, which may be welded thereto and extends circumferentially around the entire interior of the said wall. As shown, for example, in Figure 4, it is provided with a plurality of holes 14 and the space between the channel 12 and the wall 7 forms a passage which may be employed to admit a liquid or fluid. In order to permit its admission I provide an inlet sleeve or flange 15 in communication with any suitable fluid inlet pipe 16 shown in Figure 3 as passing through the walls of the member 5.

Below the channel 12 I illustrate a ring or flange 17 welded or otherwise tightly secured to the inner face of the wall 7. Clamped to it is a rubber diaphragm or ring 18 which may be secured by any suitable clamping ring 19 and the clamping bolts 20. Secured in a similar manner by a ring 19a and bolts 20a to the inner edge of the flexible diaphragm 18 is a plate, herein shown as a shallow funnel or hopper 21, although it will be realized that its shape may be widely varied. I find it advantageous, however, to have it in the form of a funnel or cone converging upon a central run-off passage member 22 which may be connected to an outlet pipe or duct 23 as by the fitting 24. The outlet pipe 23 may be of any suitable substance and, if desired it may be of rubber or yielding material, or of metal. The structure 21 may be supported, as upon concentric rings 25, 26, of metal or any other suitable material, it being understood that in the form herein shown the member or funnel 21 moves as a unit with its supporting rings 25 and 26, which may be welded thereto if desired. I illustrate also vertical plates 28 which may be welded or otherwise secured to the structure so formed. I illustrate two, diametrically opposed, as shown for example in Figures 4 and 6. Welded to the bottoms of these plates, and to the rings are horizontal plates 29. Positioned beneath each such plate are pads of rubber 30, 31. Between the two pads is positioned another block 32, as shown in detail in Figure 6. The assembly so formed is

55

clamped together by a bottom clamp member 33 held to the hub plate 29 as by bolts 34 and spacer sleeves 35. Mounted or otherwise secured to the blocks 32 are rods 36. Each such rod terminates in a bearing housing 37 to which it is adjustably secured as by the screwthreading 38 and the lock nut 39. Each such housing 37 encloses a ball or roller race 40 which has within a tapered sleeve 41 surrounding an eccentric portion 43 of a rotated shaft 42. The bearing assembly is further enclosed by a removable cover plate 44. The shaft 42 rotates in fixed bearings 45 which are shown as secured to the base structure 2. Any suitable drive pulley 46 may be employed. Instead of illustrating a unitary shaft I show two shaft portions secured together by a hollow connecting sleeve 47. It will be understood that any suitable drive may be employed whereby the pulley 46 and with it the shaft structure is rotated. The result of such rotation is to impart a substantially vertical oscillation to the rods 36. This in turn causes a substantially vertical oscillation of the member 21 and its associated parts. Its oscillation in relation to the fixed portion of the structure is permitted by the rubber ring or diaphragm 18. It will be observed from Figure 6 that there is a clearance between the upper end of each rod 36 and the locking plate 33, there being an oversize aperture 33a through which the upper end of each rod 36 passes. There is thus no binding and a slight lateral or angular movement is permitted, which is ample to take care of the movement of the device as a whole.

In order to limit any undesired tilting of the member 21 and its associated structure, on account of the rocking means of the rods 36 as they are oscillated by the rotation of the eccentrics 43, I provide balancing or equalizing springs 50. I show one at each side of the device but more could be employed if necessary. A practical arrangement, however, as shown in Figure 5, is to employ two springs 50, diametrically opposed, and midway between the rods 36. Each such spring 50 is mounted upon one of the angles 4. A suitable bottom guide 51 may be employed as a retaining stud. Penetrating the upper portion of the spring 50 is an upper guide 52 formed with a hexagonal spring abutment which may be adjustably bolted into a block 53, secured to vertical plates 54 which in turn are secured to the rings 25, 26 and to the member 21. A lock nut 55 serves to lock the screwthreaded upper guide 52 in any desired position and thus permits adjustment of the spring tension.

It will thus be observed that the space within the inner wall 7 is entirely closed by the hopper 21 and the connecting rubber ring or diaphragm 18. The top is closed by a separating or sizing bed the details of which I will now describe. Resting upon the upper flange of the channel 12 is a spider structure shown as including a plurality of radially converging double spider arms 60. Each such arm consists of twin metallic members connected by blocks 61. The arms are also welded to an outer ring 62 which in turn may be welded to the inner face of the wall 7. They are also shown as welded to an inner hub 63. If desired, I may provide cross arms 64, as shown in Figure 4 of similar structure, and also connected by intermediate blocks 61. I illustrate in Figures 3 and 8 a spider structure which is substantially horizontal. It will be understood that, where I wish to have a substantial gravitational feed, I may make the spider structure, or the bed supported upon it, or both, substantially inclined from the hori-

zontal. The bed itself includes a bottom foraminous plate or plates 65, a top plate 66, and a plurality of radial vertical partitions 67, and, if desired, additional concentric partitions 68. Thus the space between the upper and the lower foraminous plates is divided into a rather large number of separate cells or compartments. Filling each compartment is a mass of balls or similar small relatively movable particles indicated at 69. I illustrate them, as shown in Figure 8, as forming two levels or layers but a thicker or a thinner bed may be employed, depending upon the needs of a particular situation or the characteristics of a particular material being sized. The upper and lower plates are held in position on the spider structure above described, as by spacing sleeves 70 positioned in the blocks 61. Preferably these sleeves project upwardly above the upper edges of the spider members, and may be aligned with the top of the ring 62 upon which the outer edge of the foraminous structure or bottom plate 65 rests. Screwthreaded into the sleeves are securing screws 71, with heads 72 which, with washers 73, serve to hold down the upper plate and clamp the bed structure. Spacing sleeves 74 are also employed, about the screws 71, to space the upper and lower plates apart at the right distance, to prevent clamping action on the balls and to leave them enough play to permit them to perform the desired function and to allow enough movement to prevent their blinding. In other words, a relative movement of the balls in relation to each other and to the plates is necessary, but it must be confined within a range sufficient to prevent undue variation in the size of the apertures between adjacent balls, as a reasonable uniformity is necessary to obtain accurate sizing.

Upwardly projecting from the hub 63 is a central stud 80. Outwardly and upwardly extending from it are radial arms 81 which are connected at 40: their outer ends as by plates 82. These plates carry a circumferential ring 83. Clamped to the inner edge of this ring, as by clamping members 84, is a flexible inner ring 85. Clamped to the outer edge, as by the clamping members 86, is an 45: outer and much more extended flexible ring or skirt 87 which may be of rubber or the like. It extends out to the extreme edge of the bed, preferably, and may be downwardly curved at its outer edge as at 88. The outer edge of the structure 87 50: may, if desired, rest upon the outer screw heads 72. Or, if desired, it might rest on the intermediate bolt members. However, the arrangement shown in Figure 8 is practical and satisfactory and a certain clearance for the material passing 55: over the bed is desirable. If the material fills the space between the top of the bed and the member 87, its flexibility is sufficient to permit it to rise and give space for the material.

In the form of my invention illustrated in Figure 1 and following I show a structure adapted for the employment of water to keep the bed from blinding. Water is admitted through the pipe 16 and the apertures 14 and preferably fills the entire space beneath the bed, as indicated in Figure 3. The level of the water may be set by the upper edge of the wall 7 which may be described as forming a discharge lip 7a. A circulation of water is maintained and of course there will be considerable splashing as the member 21 rises and falls, squeezing water upwardly through the bed and sucking it downwardly back through the bed. This squeezing and sucking action forces water positively through the interstices of the balls and keeps them from blinding. Small particles are 75:

sucked down through and large particles are prevented from wedging in between the balls or in the apertures of the foraminous plates 65, 66. Soft material, clay and the like, is also washed out 5 in this fashion. A discharge of water over the lip 1a carries off the over size particles and the particles which pass through the bed pass off with the water down through the passage 23.

In order to feed the form of the device shown 10 in Figures 1 and following, where the discharge edge 1a passes circumferentially around the entire device, I employ a feed box 90. In order to support the feed box 90 I illustrate vertical supports 91 extending upwardly from the outer wall 15 8. They may, for example, be welded thereto. One or more angle irons 92 extend across between the members 91. Secured to them is a bearing block 93 in which is rotatably mounted a shaft 94 supported at the top as by a ball bearing structure 20 95. Secured to the lower end of the shaft 94 is a hub 96 connected by spider members 97 to the bottom of the feed hopper 90. They may, for example, be welded. 98 is a central aperture in the bottom of the feed box surrounded, for example, by a down spout 99 which passes through the center of the flexible ring 85.

150 indicates a feed pipe fixed, for example, in a bracket or lip 151 on one of the angles 92. It has a spout member 153 which is adapted to deliver water, with the mixed particles, into the feed box in such fashion that the water or particles impinge against the bottom or inner face of the side of the feed box and causes the feed box to rotate. Thus the material, for example sand, 30 35 is evenly distributed throughout the feed box and passes down the central aperture 98 and thus finds its way to the surface of the bed, for separation.

It will be understood that, whereas I have shown 40 my device as used for the operation or classification or sizing of particles carried in water, that it may also be applied to air separation or to separation of particles carried by air. It will be understood, in the first place, that the material 45 may be fed dry to the said hopper 90 or its equivalent, and may then be fed to the separating bed, water being employed otherwise as above stated. The water splashing up through the bed as the member 21 rises and falls will quickly wet the particles, and the said separation system can thus 50 be worked with dry feed.

As a further variation in method, I may dispense with the use of water altogether, and feed the material dry, and separate it dry. In that case, the air which blows up through the bed, or 55 is sucked down through the bed, as the member 21 rises or falls, performs the same function as the water. In such a case it may be desirable to employ gravity feed and to incline the bed and 60 its support toward the edge. I illustrate a variant form of my device in Figure 9 and following in which a square bed is employed, in place of a circular bed. The supporting and actuating structure is substantially the same and will not 65 be separately described, the same indicating symbols being employed. I illustrate, however, a rectangular top frame including angle members 100 supported on the corner uprights 3. Clamped to the upper horizontal flanges 101 is a rectangular 70 diaphragm 102, which may be of rubber or any suitable flexible substance. Flange 103 may be secured thereto as by bolts 104. This flange may be a part of the upper box structure or housing 105. One or more inlets 106 may admit water 75 from any suitable source. Figure 9 illustrates

one of the inlets 106 closed by a pipe plug 106a. 107 is a bottom hopper clamped to the inner edge of the diaphragm 102 as by any suitable clamping means 108. 109 is any suitable run off outlet. It is understood that the construction generally 5 follows that of Figure 1 and following. However, the reducing member 24 may directly discharge the material into any suitable chute 110 diagrammatically indicated in Figure 10.

Closing the top of a space so defined is the 10 separation bed proper which includes transverse grill members 111, conforming in detail to the spider members 60, 64 of the earlier described form. The bed structure is substantially the same except that the individual ball cells are defined 15 by a rectangular grill generally indicated as 115.

In Figure 10, I illustrate a section in which the bed is substantially horizontal. The material, water flowed, may pass over the single lateral discharge lip 116 into any suitable discharge chute 20 117. In Figure 11, to indicate air separation, I illustrate the deck or bed as substantially tilted toward the discharge edge.

Any suitable feeding means may be employed, for example a delivery chute 118, but I do not 25 illustrate them in detail.

As will be seen in Figures 9 to 11, three of the walls 119 of the housing 105 extend above the bed structure to confine and guide the material upon 30 said bed structure.

Whereas it may be under most circumstances desirable to hold the balls between two foraminous disks, 65a and 66a respectively, under some circumstances it is practical to omit the upper disk. I have done this in Figures 9 and 10, where 35 larger balls are shown. It will be understood that I may at will use or remove the top foraminous plate 66a shown, for example, in position in Figure 11. It is omitted from Figures 9 and 10.

The bed structure may be held in position upon 40 the housing 105 by bolts 120.

Referring to Figure 12, I have illustrated improved water inlet means particularly adaptable for the device illustrated in Figures 1 to 8 in order to deflect the clean incoming water upwardly and 45 towards the wall 7 of the ring structure 5. This results in obtaining in effect a wall of clean water and confining the muddy water to be discharged together with the screened material through the outlet 22. The outlets 14 of the channel 12 may 50 be provided with L-shaped tubes 125 to deflect the fluid in the direction of the arrows. However, suitable baffle plates may be positioned, adjacent the outlets 14 to deflect the water in a similar manner.

It will be realized that, whereas I have described 55 and shown a practical and operative device, nevertheless, many changes may be made in size, shape, number and disposition of parts. I, therefore, wish my description and drawings to be 60 taken as in a broad sense illustrative or diagrammatic, rather than as limiting me to the specific details of the present disclosure. It will be understood that I may employ either air or water, either a gas or a liquid, to assist in the sizing. It 65 will be also understood that a wide variety of feeding means may be employed.

Preferably the balls are round, but I can obtain my effect with balls or particles which are not strictly round. The balls or separate particles 70 may be widely varied in size and considerably varied in shape. When I employ the term "ball" in a claim, it will be understood as being intended to be interpreted with sufficient breadth to cover particles which are not actually spherical. 75

Whereas I have shown foraminous plates, it will be understood that I may, if I wish, employ screening, and, when in the claim I employ the term "screen", it will be understood as intending to include a foraminous plate or its equivalent.

In the operation of my device the suction of air, gas or water on the down-stroke of the member 21 is of great importance as it positively sucks or draws the particles down into the interstices 10 of the bed and pulls the undersize particles all the way through. It is owing to this suction action, this positive drawing of the material through the bed, that I am able to get a very great efficiency with a bed in which the proportion 15 of open area is as small as it is. For example, in a typical case, the open area of my bed may be no more than 8 per cent of the superficial area of the bed, whereas a commercial screen may have as high as 90 per cent. None the less, 20 whereas in the screen the material may have to dance around on the surface until it finds a hole, in my bed the particles are drawn into and through the spaces by positive suction.

On the upstroke of the member 21, the fluid 25 is forced through the bed, expelling any oversize particles or groupings of undersized particles which may tend to blind the bed. Inasmuch as a certain relative movement of ball in relation to ball is permitted, the cleaning of the voids is 30 much easier than it would be if all the apertures were of fixed size. Any aperture in the bed, since it is defined by relatively movable particles, varies slightly in diameter, under pressure, and permits the alternate suction and expulsion to clean the 35 pores or apertures of the bed, as it shifts their diameters.

Preferably I confine the balls or particles forming my sizing bed sufficiently to prevent their having any substantial grinding action. 40 Referring, for example to Figures 7 and 8, they may be confined between the lower screen 65 and the upper screen 66 and they are also confined laterally by the intermediate partitions 67. It will be understood, however, that I may under 45 some circumstances, especially where large balls are employed, omit the upper screen. In that case gravity, in connection with the lower screen and the lateral partitions, provides whatever confining effect is necessary. In any case, the balls must be free to have at least a limited movement 50 in response to the movement of air or liquid through the bed because, by such a movement, the freeing of the bed from blinding is obtained. But a relatively slight movement is sufficient and the possibility of a large movement would have 55 the two-fold disadvantage of causing undesired grinding and degradation and also of causing variation in the size of the particles passing through the bed. When, in any claim I describe 60 the balls or particles as confined it will be understood that I mean not a complete confinement of the particles against movement but confinement sufficient no matter how obtained, to hold the balls against excess and undesired movement, 65 while permitting to the individual balls sufficient movement to obtain the desired effect.

In the operation of the device it will be understood that either air or water may be employed. Where air is employed, the deck or separating member is preferably inclined toward the discharge lip, as shown, for example, in Figure 11. It will be further understood that, where air is employed, the air trapped in the space between the separating member or deck and the member 75 107 of Figure 11, to give one example, is sufficient

to obtain my result, and I do not have to provide additional air under pressure. When I employ water as a medium, the supply has to be maintained, preferably constantly, by the addition of further water, as through the pipe 16 of 5 Figure 3; since water is continually passing over the discharge lip and flowing into the trough 5. I may employ any suitable check valve 109a in the line 109 in order to limit the flow of liquid through the said line.

A further use of my sizing device consists in the employment of the screens themselves, the mesh 65 and 66, or a single screen, where only one is used, as in Figure 9, to size or separate the particles, while employing the balls, or their 15 equivalent, as means for maintaining the mesh clear and unblinded. In such case, where the mesh of the screen determines the size of the particles and not the interstices between the balls, the balls need not abut, or a greater freedom of 20 movement may be allowed the balls, and a great range in the size of the balls. In such case, the primary function of the balls is not to determine the size of the particles which pass through the 25 sizing bed, but to insure that the apertures of the screen are kept unblinded.

I claim:

1. In a sizing device, a sizing bed which includes a plurality of abutting balls of uniform size and shape, arranged in a relatively thin layer, means for holding said balls against substantial relative movement while permitting a slight movement of individual balls, the interstices between balls constituting sizing apertures, means for delivering to the top of the bed the 35 material to be sized, and means for clearing the interstices of the bed, and for drawing the fine particles downwardly through the bed, including a moveable member, a fluid in the space between the bed and the moveable member, and means for 40 imparting movement to the moveable member and for thereby causing the fluid to move alternately in opposite directions through the bed, the top of the bed being free from projections which would prevent the free discharge of oversize particles.

2. In a sizing device, a sizing member, means for delivering to the sizing member the material to be sized; a pulsating member positioned beneath the sizing member, means for maintaining the space between the pulsating member and the sizing member filled with a liquid, means for reciprocating said pulsating member and thereby causing the liquid to move alternately in opposite directions through the sizing member, said pulsating member including a hopper and a flexible diaphragm connection between the upper edge of said hopper and the rest of the sizing device, adapted to cooperate as a portion of said hopper, the sizing member including a plurality of abutting balls of generally uniform size and shape arranged in a relatively thin layer, and means for holding said balls against substantial relative movement while permitting a slight movement of the individual balls, the interstices between balls constituting the sizing apertures.

3. The method of sizing particles which includes maintaining, in a sizing zone, a plurality of substantially contacting, relatively movable members of substantially uniform size and shape, whereby the apertures between adjacent members are of substantially uniform cross section, restricting the movement of said members to permit a slight relative movement, while preventing any substantial variation in the cross-sectional 75

- area of the apertures therebetween, causing a fluid to flow through the zone of separation alternately in opposite directions, drawing the undersized particles by suction of the fluid downwardly 5
- 5 through the sizing zone, carrying off the oversized particles across the upper face of said zone, and carrying off the undersized particles from beneath said zone.
4. In a sizing device, a sizing member which 10 includes an upper pervious partition and a lower pervious partition, and a body of balls of substantially uniform size positioned between said two partitions whereby the apertures between adjacent balls are substantially uniform in cross 15 sectional area and constitute sizing apertures, the balls substantially filling the area between said partitions, sufficient room being left to permit a slight relative movement of the balls, and means for maintaining a body of liquid at a level 20 corresponding generally to the level of the upper pervious partition and means for pulsating said liquid.
5. In a sizing device, a sizing member which 25 includes an upper pervious partition and a lower pervious partition, a body of balls of substantially uniform size positioned between said two partitions whereby the apertures between adjacent balls are substantially uniform in cross sectional area and constitute sizing apertures, the balls 30 substantially filling the area between said partitions, sufficient room being left to permit a slight relative movement of the balls, and means for maintaining a body of liquid at a level corresponding generally to the level of the upper pervious partition, including a lip terminating generally at the level of said upper pervious partition and means for pulsating said liquid.
6. In a sizing bed, upper and lower spaced 35 foraminous members, a plurality of balls of substantially uniform size arranged in superposed layers in the space between said foraminous members and substantially filling the space therebetween, the interstices between balls constituting sizing apertures smaller than the apertures in said foraminous members, said foraminous members being adapted by their close approach to permit slight relative movement of the balls while preventing movement sufficient to vary the cross sectional area of the apertures between adjacent balls, the bed so formed being 40 adapted for the pulsation of a fluid therethrough.
7. In a sizing device, a bed, including a plurality of abutting balls of substantially uniform size arranged in a relatively thin layer, the interstices between balls being substantially uniform in size and constituting sizing apertures, means for delivering to the bed the material to be sized, and means for clearing the interstices of the bed, including a movable member, a fluid 45 in the space between the bed and the movable member, means for imparting movement to the movable member and for thereby causing said fluid to move alternately in opposite directions through the bed, and means for limiting the balls to a movement insufficient substantially to change the gauge of the apertures between the balls.
8. In a sizing device, a sizing bed which 50 includes a plurality of abutting balls of uniform size and shape, arranged in a relatively thin layer, means for holding said balls against substantial relative movement while permitting a slight movement of individual balls, the interstices between balls constituting sizing apertures, means for delivering to the top of the bed the material to be sized, and means for clearing the 55 interstices of the bed, and for drawing the fine particles downwardly through the bed, including a movable member, a fluid in the space between the bed and the movable member, and means for imparting movement to the movable member and for thereby causing the fluid to move alternately in opposite directions through the bed, the top of the bed being free from projections which would prevent the free discharge of oversize particles, and a discharge edge member for the bed, 60 remote from the area of the feed and lying at the general level of the bed.
9. In a sizing device, a sizing bed which 65 includes a plurality of abutting balls of uniform size and shape, arranged in a relatively thin layer, means for holding said balls against substantial relative movement while permitting a slight movement of individual balls, the interstices between balls constituting sizing apertures, means for delivering to the top of the bed the material to be sized, and means for clearing the interstices of the bed, and for drawing the fine particles downwardly through the bed, including a movable member, a fluid in the space between the bed and the movable member, and means for imparting movement to the movable member and for thereby causing the fluid to move alternately in opposite directions through the bed, the top of the bed being free from projections which would prevent the free discharge of oversize particles, and a discharge edge member for the bed, 70 remote from the area of the feed and lying at the general level of the bed.
10. In a sizing device, a sizing bed which 75 includes spaced upper and lower pervious members, and a plurality of substantially uniformly sized balls located in and substantially filling said space, whereby the apertures between adjacent balls are substantially uniform in cross sectional area, and constitute sizing apertures of a smaller gage than the apertures of said pervious members, there being sufficient space in said bed to permit a slight relative movement of said balls, the top of the bed being free from projections which would prevent the free discharge of oversize particles across and from the top of said bed, said bed being adapted for the passage of a fluid therethrough.
11. In a sizing device, a sizing bed which 80 includes spaced upper and lower pervious members, and a plurality of substantially uniformly sized balls located in and substantially filling said space, whereby the apertures between adjacent balls are substantially uniform in cross sectional area, and constitute sizing apertures of a smaller gage than the apertures of said pervious members, there being sufficient space in said bed to permit a slight relative movement of said balls, the top of the bed being free from projections which would prevent the free discharge of oversize particles across and from the top of said bed, said bed being adapted for the passage of a fluid therethrough, and means for pulsating a fluid through said bed and for thereby causing a slight movement of said balls and causing a suctional withdrawal of fine particles downwardly through said bed.
12. In a sizing device, a sizing bed which 85 includes spaced upper and lower pervious members, and a plurality of substantially uniformly sized balls located in and substantially filling said space, whereby the apertures between adjacent balls are substantially uniform in cross sectional

- area, and constitute sizing apertures of a smaller gage than the apertures of said pervious members, there being sufficient space in said bed to permit a slight relative movement of said balls, 5 the top of the bed being free from projections which would prevent the free discharge of oversize particles across and from the top of said bed, said bed being adapted for the passage of a fluid therethrough, and an impervious cover extending across the top of said bed and terminating adjacent the discharge edge thereof and means for feeding material to be separated to the top of the upper pervious member, and beneath said impervious cover.
- 10 13. In a sizing device, a sizing bed which includes spaced upper and lower pervious members, and a plurality of substantially uniformly sized balls located in and substantially filling said space, whereby the apertures between adjacent 15 balls are substantially uniform in cross sectional area, and constitute sizing apertures of a smaller gage than the apertures of said pervious members, there being sufficient space in said bed to permit a slight relative movement of said balls, 20 25 the top of the bed being free from projections

which would prevent the free discharge of oversize particles across and from the top of said bed, said bed being adapted for the passage of a fluid therethrough, said upper and lower pervious members constituting foraminous plates. 5

14. In a sizing device, a sizing bed which includes spaced upper and lower pervious members, and a plurality of substantially uniformly sized balls located in and substantially filling said space, whereby the apertures between adjacent 10 balls are substantially uniform in cross sectional area, and constitute sizing apertures of a smaller gage than the apertures of said pervious members, there being sufficient space in said bed to permit a slight relative movement of said balls, 15 the top of the bed being free from projections which would prevent the free discharge of oversize particles across and from the top of said bed, said bed being adapted for the passage of a fluid therethrough, said upper and lower pervious 20 members constituting foraminous plates, the apertures of said plates being of substantially greater length than width. 25
